(57) **CLAIM**

The ornamental design for an automatic timer as shown and described.

DESCRIPTION

Fig. 1 is a perspective view of an automatic timer showing the new design;

Fig. 2 is another perspective view thereof;

Fig. 3 is a front elevation view thereof;

Fig. 4 is a back elevation view thereof;

Fig. 5 is a left view thereof;

Fig. 6 is a right view thereof;

Fig. 7 is a top plan view thereof; and

Fig. 8 is a bottom plan view thereof.

The broken lines depict portions of the automatic timer that form no part of the claimed design.
